Primary Examiner — Clare E Heflin(74) *Attorney, Agent, or Firm* — Anatoly S. Weiser, Esq.; IPLCounsel.com(57) **CLAIM**

The ornamental designs for an LED lighting fixture, as shown and described.

DESCRIPTION

FIG. 1 is a perspective view of the LED lighting fixture showing the new design with a snap-on accessory trim piece installed;

FIG. 2 is a top plan view thereof;

FIG. 3A is a front side view thereof, the rear side view being the same;

FIG. 3B is an enlarged fragmentary view thereof, taken from the circle 3B in FIG. 3A;

FIG. 4 is a right side view thereof, the left side view being the same; and

FIG. 5 is a bottom plan view thereof.

FIG. 6 is a perspective view of the LED lighting fixture showing the new design with the snap-on accessory trim piece removed;

FIG. 7 is a top plan view thereof;

FIG. 8 is a front side view thereof, the rear side view being the same;

FIG. 9 is a right side view thereof, the left side view being the same; and,

FIG. 10 is a bottom plan view thereof.

The broken lines shown on the drawings depict portions of the LED lighting fixture that form no part of the claimed design.
